UNITED STATES PATENT OFFICE

SAMUEL GATES, OF BROOKLYN, NEW YORK

DESIGN FOR A COMBINATION PAJAMA JACKET AND DICKY

Application filed December 10, 1929. Serial No. 33,730. Term of patent 7 years.

To all whom it may concern:

Be it known that I, SAMUEL GATES, a citizen of the United States, residing at Brooklyn, in the county of Kings and State of New York, have invented a new, original, and ornamental Design for a Combination Pajama Jacket and Dicky, of which the following is a specification, reference being had to the accompanying drawings, forming part thereof.

The figure is a plan view of a combination pajama jacket and dicky, showing my new design.

I claim:

The ornamental design for a combination pajama jacket and dicky as shown.

SAMUEL GATES.
